UNITED STATES PATENT OFFICE

161,872

EARRING OR THE LIKE

Yvonne Roditi-Melli, New York, N. Y., assignor to Coro, Inc., New York, N. Y., a corporation of
 New York

Application June 30, 1950, Serial No. 10,849

Term of patent 7 years

(Cl. D45—9)

To all whom it may concern:

Be it known that I, Yvonne Roditi-Melli, a citizen of the United States of America, residing in New York, county of New York, and State of New York, have invented a new, original, and ornamental Design for an Earring or the like, of which the following is a specification, reference being had to the accompanying drawing, forming part thereof.

Fig. 1 is a plan view of an earring or the like, showing my new design.

Fig. 2 is an edge view thereof.

Fig. 3 is a perspective view of the earring as shown in Fig. 1.

I claim:

The ornamental design for an earring or the like, substantially as shown.

YVONNE RODITI-MELLI.
